PRODUCTION OF MAGNETIC RECORDING
MEDIA USING COPOLYAMIDE BINDER
FOR FERROMAGNETIC POWDER

3 Claims. (Cl. 117—138.8)

ABSTRACT OF THE DISCLOSURE

Manufacture of magnetic recording media in which a ferromagnetic powder is applied to a film in admixture with a linear polyamide binder composed of 50 to 100% by weight (with reference to the total weight of the binder) of monomeric units which are salts of (A) omega, omega'-octane- or omega,omega'-nonane-dicarboxylic acids bearing an aliphatic hydrocarbon substituent of 8 or 9 carbon atoms in a continuous chain and (B) diamines of 8 to 20 carbon atoms. An example of the essential polyamide-forming component is the salt of heptadecane dicarboxylic acid and p,p'-diaminocyclohexylmethane.

This invention relates to a process for the production of layered magnetic recording media comprising one or more layers of magnetizable powdered substances and a binder of copolyamides for video, impulse and sound recording.

The preparation of magnetic recording media by coating a backing, such as a sheet, a wire or a filament of plastics or metal, with a dispersion of a magnetizable substance is known in which film-forming substances, such as cellulose ethers, cellulose esters, polyvinyl chloride, polyesters, polyurethanes or solvent-soluble cocondensation products of a plurality of components forming linear polyamides are used as binders.

It has been found that the plastics used do not always satisfy technical requirements, such as abrasion resistance, mechanical and chemical resistance, resistance to high temperatures, compatibility with the magnetizable substance and dimensional stability.

We have found that magnetic recording media having particularly advantageous properties for magnetic video, impulse and sound recording can be prepared by application of ferromagnetic powders which are suspended in a solution of a binder comprising a cocondensation product of a plurality of components forming linear polyamides, to a sheet, with or without the use of an adhesion agent, by using as the binder a copolyamide which contains in polymerized form, with reference to the total weight of the polyamides, 50 to 100% of linear polyamide forming components having eight to twenty carbon atoms. Copolyamides are polyamides which have been obtained by polymerizing a mixture of different polyamide forming components.

Magnetic recording media prepared according to this invention have inter alia a high abrasion resistance and good dimensional stability.

Examples of suitable components having eight to twenty carbon atoms which form linear polyamides are capryllactam, capric lactam, laurolactam, branched lactams bearing substituents on carbon: C-ethyl-epsilon-caprolactam, C-ethyl-zeta-oenantholactam, the amino-

2

carboxylic acids of these lactams; mixtures or salts of aliphatic dicarboxylic acids, which may be branched, such as suberic acid, azelaic acid, sebatic acid, dodecane dicarboxylic acid, α -ethylsuberic acid, or other branched dicarboxylic acids, such as α,α' -diethyladipic acid, or preferably omega,omega'-octane or -nonane dicarboxylic acids which contain as substituents higher aliphatic hydrocarbon radicals having at least eight or nine carbon atoms in a continuous chain and which may be prepared for example according to the process of German Patent Specification No. 1,006,849, or aromatic dicarboxylic acids, such as isophthalic acid, and diamines, such as octamethylene diamine, nonamethylene diamine, decamethylene diamine, which, like the dicarboxylic acids, may bear aliphatic or aromatic radicals, for example m-xylene diamine or 4,4'-diaminodicyclohexylmethane. The said compounds may be used mixed with each other or mixed with other components which form linear polyamides, such as caprolactam, adipic acid, pentamethylene diamine, hexamethylene diamine and their C-substituted derivatives or salts or mixtures of the last-mentioned dicarboxylic acids and the diamines.

The dispersion which contains the magnetizable substance and the dissolved polyamide to be used according to this invention is preferably prepared by a conventional method by homogenizing the ferromagnetic material with the solvent and binder, for example in a ball mill.

The ratio of ferromagnetic material to binder may be varied within wide limits, for example from 2:1 to 5:1, preferably from 3:1 to 4:1.

Magnetite, acicular iron oxide ($\text{gamma-Fe}_2\text{O}_3$) or metallic substances, such as iron powder, are suitable ferromagnetic substances.

Solvents conventionally used for polyamides or mixtures thereof with swelling agents and non-solvents are suitable, for example aliphatic alcohols, such as methanol, ethanol, propanol, isopropanol, n-butanol, isobutanol; araliphatic alcohols, such as benzyl alcohol or mixtures thereof with water, aromatic and aliphatic hydrocarbons, esters, ketones, glycol ethers, ether nitriles, or mixtures which may consist of two or three of the said compounds, for example alcohols with water, aromatics, water and alcohols, such as benzene/methanol/water.

The type of solvent or solvent mixture used depends on the type of copolyamide used according to the invention.

Polyesters, polyvinyl chloride and celluloseacetate are suitable as backing for the magnetizable layer.

The magnetizable layer is applied to the backing by conventional methods. For example the ferromagnetic layer may be united with the backing by application by means of rollers or by pouring the dispersion.

The good compatibility of the binder used according to this invention with the magnetizable material, for example with acicular iron oxide, makes it possible to distribute the iron oxide particles uniformly without changing their magnetic properties.

Moreover these magnetizable layers have a high surface smoothness with a uniformly high pigment density (grams of iron oxide particles per cc.).

An advantage resulting from this is that magnetic recording media provided with such a layer cause extremely low wear on the recording and reproducing heads. The life of the magnetic head is more than five times as long when using layered magnetic recording media having binders according to this invention than when using prior art magnetic recording media. The wear of a magnetic recording medium prepared with a binder according to this invention is compared below with that of mag-

netic recording media which have been prepared with prior art binders:

Binder	Wear of head in mg. per 1000 m. of tape
According to this invention	0.06 to 0.07
Polyurethane	0.11
Polyvinyl chloride	0.23

Wear of recording and reproducing heads is determined by the following method: A loop 20 m. in length of a magnetic recording medium in tape form is passed at constant speed over a small circular plate of Mu-metal (a material used for manufacturing recording heads) while being pressed against it with a pressure of 60 g. Wear of the small plate is determined by microscopic measurement of the length of the chord at the point of abrasion and calculating the decrease in weight therefrom.

Binders according to this invention moreover have high abrasion resistance which is clearly superior to that of binders hitherto used.

The abrasion values of prior art binders are compared in the following table with the abrasion value of a binder according to this invention:

TABLE

Binder used	Abrasion in microns
Polyvinyl chloride	1.4
Copolymer based on vinyl chloride and vinyl acetate in the ratio 1:1	1.1
Copolymer based on styrene and acrylonitrile in the ratio 78:22	1.0
Polyurethane resin	0.8-0.9
Binder according to this invention (Example 1)	0.6-0.7

Abrasion resistance is determined by the following method: A magnetic recording medium in tape form with a definite magnetization is passed over a defined roughened surface while being pressed against it under a defined pressure. The decrease in layer thickness of the tape is determined by electroacoustic measurement of the decrease in sensitivity.

Adhesion of the binder to be used according to this invention to the backing, for example of polyvinyl chloride, acetyl cellulose or polyester based on terephthalic acid and ethylene glycol, may be improved by the use of an adhesion agent of polyesters soluble in solvents. Polycondensates having a K-value of 30 to 40 and prepared from terephthalic acid, isophthalic acid and ethylene glycol are particularly suitable as adhesion agents. The adhesion agent is applied in the conventional way by means of rollers.

When more than one superposed layer of magnetizable substance is used, it is only necessary to use a binder according to this invention in the layer which comes into contact with the recording or reproducing head, without the quality being affected.

The invention is illustrated by the following examples. The parts specified in the examples are parts by weight.

Example 1

6 parts of acicular iron oxide ($\text{gamma-Fe}_2\text{O}_3$) having a particle size of 0.8 to 1 micron and a coercive force of 300 oersteds is homogenized with a solution of 2.3 parts of a condensation product of a mixture of 80 parts of a salt of heptadecane dicarboxylic acid and p,p'-diaminodicyclohexylmethane and 20 parts of capryllactam (K-value 50, measured according to H. Fikentscher, Cellulose-chemie, 13, 58 (1932)), 15 parts of a mixture of 90 parts by volume of ethanol and 10 parts by volume of benzene with an addition of 0.1 part of a mixture of emulsifiers consisting of triethanolamine monooleic acid ester and the corresponding diesters and triesters. The dispersion is applied to a polyester film (based on terephthalic acid and ethylene glycol) having a thickness of 20 microns in the conventional way with the simultaneous action of a magnetic field. The thickness of the dry magnetic recording layer on the polyester foil is 12 microns. The iron

ture of 50 parts by volume of toluene and 50 parts by volume of n-propanol in the presence of 24 parts of stearic acid as dispersing agent. The dispersion is applied under the action of a magnetic field to a polyester film having a thickness of 24 microns which has been provided with a layer about 0.5 micron in thickness of the adhesion agent described in Example 3, and the coated film is calendered. The thickness of the magnetic recording layer is 9 microns and the content of iron oxide is 1.9 g./cc. The abrasion of the magnetizable layer is 0.8 micron. The wear on the magnetic head is less than 0.06 mg.

At a tape speed of 38 cm./sec. a sensitivity of -2.6 db, a frequency response of +3.6 db (with reference to DIN standard tape 38 (DIN 45513)) and a harmonic distortion of 29 db are measured according to the broadcast-
ing conditions (ibid.).

Example 5

600 parts of the iron oxide described in Example 1 is ground with a solution of 200 parts of a condensation product having a K-value of 41.7 and obtained from a mixture of 80 parts of a salt of heptadecane dicarboxylic acid and p,p'-diaminodicyclohexylmethane and 20 parts of caprolactam, 900 parts of a solvent mixture of 50 parts by volume of toluene, 30 parts by volume of n-propanol and 20 parts by volume of ethanol in the presence of 24 parts of stearic acid in a conventional way to form a dispersion which is applied to a polyester film having a thickness of 24 microns while being exposed to a magnetic field and dried. The layer applied has a thickness of 10 microns and an iron oxide concentration of 1.7 g./cc. Abrasion of the layer is 0.70 micron and wear on the magnetic head is 0.07 mg.

Example 6

35 A solution of 100 parts of a condensation product having a K-value of 51.9 and obtained from 60 parts of a salt of heptadecane dicarboxylic acid and p,p'-diaminodicyclohexylmethane, 20 parts of caprolactam and 20 parts of AH-salt (from adipic acid and hexamethylene diamine), 300 parts of the acicular iron oxide described in Example 1 and 900 parts of a solvent mixture of 50 parts by volume of toluene and 50 parts by volume of n-propanol, are ground to a dispersion by a conventional method. This is applied under the action of a magnetic field to a backing of polyethylene terephthalate and dried.

The thickness of the magnetic recording layer is 13 microns, the content of iron oxide is 1.6 g./cc., the layer abrasion is 0.63 micron and the wear on the magnetic head is 0.07 mg.

We claim:

1. An improved magnetic recording media of high abrasion resistance comprising a filmaceous base to which there has been applied a ferromagnetic powder admixed in a binder consisting of a linear polyamide containing at least 50 up to 100% by weight (with reference to the total weight of the binder) of monomeric units selected from the class consisting of the salts of (A) omega, omega'-octane- and omega,omega'-nonane-dicarboxylic acids bearing an aliphatic hydrocarbon substituent of 8 to 9 carbon atoms in a continuous chain, and (B) diamines of 8 to 20 carbon atoms.
2. A magnetic recording media as claimed in claim 1 wherein said binder consists essentially of a linear polyamide of the components heptadecane dicarboxylic acid and p,p'-diaminocyclohexylmethane.
3. A magnetic recording media as claimed in claim 1 wherein said filmaceous base is a polyester of terephthalic acid and ethylene glycol.
